FENCE POST

Filed July 19, 1928

Patented Mar. 5, 1929.

1,704,644

UNITED STATES PATENT OFFICE.

WILLIAM C. ACHTERKIRCH, OF OGILVIE, MINNESOTA.

FENCE POST.

Application filed July 19, 1928. Serial No. 293,988.

This invention relates to a fence post and it is an object of the invention to provide a device of this kind wherein the fence fabric or strands will be readily locked or secured thereto without the use of staples or kindred fastening elements.

It is also an object of the invention to provide a post of this kind which can be readily produced from metal in a manner wherein 10 the weight of the post is of pronounced lightness, or desirable weight.

Another object of the invention is to provide a post of this kind constituting an elongated metallic bar together with a separable 15 point to facilitate the proper spacing of the post in desired working position.

A still further object of the invention is to provide a post of this kind embodying means whereby the same is effectively anchored within the ground and in a manner to 20 materially reduce the liability of the post falling.

The invention consists in the details of construction and in the combination and arrangement of the several parts of my improved fence post whereby certain important 25 advantages are attained and the device rendered simpler, less expensive and otherwise more convenient and advantageous for use, 30 as will be hereinafter more fully set forth.

The novel features of my invention will hereinafter be definitely claimed.

In order that my invention may be the better understood, I will now proceed to describe 35 the same with reference to the accompanying drawings, wherein:—

Figure 1 is a view in perspective of a post constructed in accordance with an embodiment of my invention;

40 Figure 2 is a view partly in section and partly in side elevation of the post as illustrated in Figure 1, the line of section being taken lengthwise of the post;

Figure 3 is a sectional view taken substantially on the line 3—3 of Figure 1;

Figure 4 is a view in perspective of the lower portion of the retaining slide;

Figure 5 is a longitudinal sectional view taken through the upper portion of the post 50 with the fabric holding plate applied.

As disclosed in the accompanying drawings, my improved post comprises an elongated channel member M of requisite dimensions and which has each of its side walls 1 defined by an inwardly disposed flange 2.

These side walls 1 are provided therewith with a series of longitudinally spaced slots 3 opening through an adjacent flange 2 and in which are adapted to be arranged the wire strands of a fence structure. These slots 3 are disposed on a desired downward incline with the inner or closed end portion of each of the slots provided with a depending branch 4 in which a wire strand is adapted to seat when in applied or working position with respect to the post.

60 The top of the post is adapted to be closed by a plate 5 riveted, as at 6, for otherwise connected to an arm or plate 7 carried by an end portion of an elongated slide or holding member 8. The plate 7 is herein disclosed as at right angles to the elongated member or slide 8. The slide or member 8 is of a width to bridge the space between the flanges 2 and to overlie the inner faces of said flanges when the slide or member 8 is applied.

65 The slide or member 8 is of a length, when the plate or cap 5 is in contact with the upper end of the member M, to extend along said member to a point beyond or below the innermost slots 3 so that the wire strands engaged within such slots will be effectively held against displacement. The lower portion of the slide or member 8 is provided with an outwardly and downwardly directed neck 9 of a width to freely extend between the inturned flanges 2, the outer end portion of the neck 70 carrying a cross head 10 the end portions of which having close contact with the outer faces of the flanges 2, thus providing means 75 to overlie the inner faces of the flanges 2 and to overlie the inner faces of said flanges when the slide or member 8 is applied.

75 The slide or member 8 is of a length, when the plate or cap 5 is in contact with the upper end of the member M, to extend along said member to a point beyond or below the innermost slots 3 so that the wire strands engaged within such slots will be effectively held against displacement. The lower portion of the slide or member 8 is provided with an outwardly and downwardly directed neck 9 of a width to freely extend between the inturned flanges 2, the outer end portion of the neck 90 carrying a cross head 10 the end portions of which having close contact with the outer faces of the flanges 2, thus providing means 90 to overlie the inner faces of the flanges 2 and to overlie the inner faces of said flanges when the slide or member 8 is applied.

95 The lower end portion of the slide or member 8 above the neck 9 but in relatively close proximity thereto carries a forwardly directed block 11 also freely engaging within the space between the flanges 2. To the outer face of this block 11 is secured by the bolts 12 or the like a cross member 14, the extremities of which also having close contact with the outer faces of the flanges 2 to further maintain the lower portion of the slide or member 100 100 being maintained in operative position. The bolts 12, as herein disclosed, also serve to hold the block 11 in applied or working position.

105 The outer end portion of the plate 7 at the 110

upper end of the slide or member 8 is continued by the inwardly disposed extension plate 15 inclined in a direction toward the slide or member 8, said extension plate 15 readily 5 passing within the upper end of the member M as the slide or member 8 is moved downwardly and assuring the plate 6 having requisite close engagement within the upper portion of the member M to maintain the top part 10 of the slide or member 8 in desired working position.

When it is desired to attach a fence fabric to my improved post, said fabric is properly disposed across the open face of the member M 15 and the applied slide or member 8 and a holding or clamping plate A is then disposed over the fabric and held to the slide or member 8 by the bolts 16 or the like, each disposed through a suitable opening 17 in the plate A 20 and threaded through the slide or member 8.

The lower end portion of the member M has snugly inserted therein a reduced shank 18 of a puncturing point 19, said point being held in applied position by a rivet 20 or the like 25 disposed through a side wall 1 of the member M and engaging the shank 18.

The side walls 1 of the member M at a desired distance above the lower end thereof are provided with the transversely aligned and 30 longitudinally disposed slots 21 through which is directed an anchor plate 22. This plate 22 extends a desired distance beyond the opposite sides of the member M and the outer margins of said plate are inclined downwardly toward the member M on a predetermined 35 incline.

In placing the post the plate 1 is arranged a desired distance within the ground, thus assuring effective maintenance of the post in 40 desired position.

From the foregoing description it is thought to be obvious that a fence post constructed in accordance with my invention is particularly well adapted for use by reason 45 of the convenience and facility with which it may be assembled and operated, and it will also be obvious that my invention is susceptible of some change and modification without departing from the principles and spirit 50 thereof and for this reason I do not wish to be understood as limiting myself to the precise arrangement and formation of the several parts herein shown in carrying out my invention in practice except as hereinafter 55 claimed.

I claim:—

1. A fence post comprising an elongated channel member, the free marginal portions of the side walls of said member being defined 60 by inwardly disposed flanges, said side walls being provided therealong with slots opening through the flanges, a slide extending within the member through the top thereof and bridging the space between the flanges of the 65 side walls and contacting with the inner faces

thereof, means carried by the inserted end portion of the slide extending outwardly between the flanges and contacting with the outer faces of the flanges for holding the lower portion of the slide in applied position, 70 and a cap plate carried by the outer end portion of the slide for closing the upper end of the member. 75

2. A fence post comprising an elongated channel member, the free marginal portions 80 of the side walls of said member being defined by inwardly disposed flanges, said side walls being provided therealong with slots opening through the flanges, a slide extending within the member through the top thereof and bridging the space between the flanges of the side walls and contacting with the inner faces thereof, means carried by the inserted end portion of the slide extending outwardly between the flanges and contacting with the outer faces of the flanges for holding the lower portion of the slide in applied position, 85 a cap plate carried by the outer end portion of the slide for closing the upper end of the member, the upper end portion of the slide being provided with an angularly disposed plate to which the cap plate is secured, said angularly disposed plate snugly fitting within the upper portion of the member when the cap plate is engaged with the top of the member. 90

3. A fence post comprising an elongated channel member, the free marginal portions 95 of the side walls of said member being defined by inwardly disposed flanges, said side walls being provided therealong with slots opening through the flanges, a slide extending within the member through the top thereof and bridging the space between the flanges of the side walls and contacting with the inner faces thereof, means carried by the inserted end portion of the slide extending outwardly between the flanges and contacting with the outer faces of the flanges for holding the lower portion of the slide in applied position, 100 a cap plate carried by the outer end portion of the slide for closing the upper end of the member, the upper end portion of the slide being provided with an angularly disposed plate to which the cap plate is secured, said angularly disposed plate snugly fitting within the upper portion of the member when the cap plate is engaged with the top of the member, 105 the outer extremity of said angularly disposed plate being continued by an inwardly directed extension plate inclined in a direction toward the slide. 110

4. A fence post comprising an elongated channel member, the free marginal portions 115 of the side walls of said member being defined by inwardly disposed flanges, said side walls being provided therealong with slots opening through the flanges, a slide extending within the member through the top thereof and bridging the space between the flanges of the 120 member. 125

side walls and contacting with the inner faces thereof, means carried by the inserted end portion of the slide extending outwardly between the flanges and contacting with the outer faces of the flanges for holding the lower portion of the slide in applied position, a cap plate carried by the outer end por-

tion of the slide for closing the upper end of the member, an elongated holding plate, and means for securing said holding plate in position along the slide. ¹⁰

In testimony whereof I hereunto affix my signature.

WILLIAM C. ACHTERKIRCH.
